SWEATER ENSEMBLE

Nathan K. Morris, Avon, N. J.

Application October 12, 1953, Serial No. 27,145

Term of patent 14 years

(Cl. D3—4)

To all whom it may concern:

Be it known that I, Nathan K. Morris, a citizen of the United States of America, residing at the city of Avon, county of Monmouth, and State of New Jersey, have invented a new, original, and ornamental Design for a Sweater Ensemble, of which the following is a specification, reference being had to the accompanying drawing, forming a part thereof.

I claim:

The ornamental design for a sweater ensemble, as shown.

NATHAN K. MORRIS.
